UNITED STATES PATENT OFFICE.

GEORGE WESLEY EARNEST, OF BEDFORD, PENNSYLVANIA.

CAP FOR MUCILAGE-BOTTLES.

1,303,179.

Specification of Letters Patent.

Patented May 6, 1919.

Application filed July 12, 1918. Serial No. 244,605.

To all whom it may concern:

Be it known that I, GEORGE WESLEY EARNEST, a citizen of the United States, residing at Bedford, in the county of Bedford and State of Pennsylvania, have invented new and useful Improvements in Caps for Mucilage-Bottles, of which the following is a specification.

This invention is an improved cap for use as a closure on the neck and mouth of a mucilage bottle and to prevent waste of the mucilage and to also prevent the mucilage from hardening and gumming the brush, the object of the invention being to provide an improved device of this character which is simple in construction and is strong and durable.

With the above and other objects in view the invention consists in the construction, combination and arrangement of devices hereinafter described and claimed.

In the accompanying drawings:—

Figure 1 is a vertical sectional view of a cap constructed in accordance with my invention and showing the same arranged for use on the neck of a mucilage bottle and in connection with the brush.

Fig. 2 is a similar view of the same at right angles to Fig. 1.

Fig. 3 is a plan of the same.

The cap 1 may be made of any suitable material and is arranged to fit tightly around the neck of a mucilage bottle and is provided with a central opening 2 through which the mucilage brush 3 extends. On the cap and at opposite sides of the opening are guide pieces 3 which form guide grooves 4. A slide 5 is movable in the guide grooves and may be moved inwardly to close the opening 2 or outwardly to uncover said

opening, either completely or to any desired extent.

The cap is also provided with an inner tubular portion 6 which is concentric therewith and which extends down into the neck 45 of the bottle and is provided near the lower end with a scraper pin or bar 7. A cork or other suitable element 8 is arranged in the cap to bear on the mouth of the bottle and effect a tight joint between the cap and the 50 mouth of the bottle.

The brush when it is drawn upwardly presses against the bar so that superfluous mucilage is scraped from the brush and caused to drop back into the bottle. The 55 brush is also scraped between one side of the opening 2 and the rounded inner end of the slide 5 so that the brush is kept clear and mucilage is prevented from hardening thereon. When the brush is entirely withdrawn from the bottle and cap, the slide 5 may be closed. The said slide in connection with the opening 2 may also be arranged to hold the brush at any desired place in the bottle either partially submerged in the mucilage or arranged above the level of the mucilage.

Having thus described my invention, I claim:

A mucilage bottle cap having an exterior 70 flange to fit around the neck of the bottle and being provided with a central opening for the passage of a brush handle, a cylindrical member depending from said cap in spaced relation to said flange, and a trans- 75 verse pin extending centrally across said member and serving as a scraper element.

In testimony whereof I affix my signature.

GEORGE WESLEY EARNEST.
